United States Patent Office

Des. 212,381
Patented Oct. 8, 1968

212,381

LIGHT FIXTURE

Buell Moore, Houston, Tex., assignor to Esquire, Inc.,
New York, N.Y., a corporation of Delaware

Filed Jan. 3, 1968, Ser. No. 10,044

Term of patent 14 years

(Cl. D48—20)

FIG. 1 is a perspective view as seen from one corner and the bottom of a light fixture embodying my design;

FIG. 2 is a perspective as seen from the opposite corner and the top of such light fixture;

FIG. 3 is a perspective view from the bottom and one end of such light fixture; and

FIG. 4 is a perspective view from the bottom and other end of such light fixture.

The broken line showing in FIGS. 1 and 2 is for illustrative purposes only.

I claim:

The ornamental design for a light fixture, substantially as shown and described.
